UNITED STATES PATENT OFFICE.

OSCAR H. PIEPER AND ALPHONSE F. PIEPER, OF ROCHESTER, NEW YORK.

FLUID-PUMP.

1,203,651.

Specification of Letters Patent. Patented Nov. 7, 1916.

Application filed February 7, 1914. Serial No. 817,192.

To all whom it may concern:

Be it known that we, OSCAR H. PIEPER and ALPHONSE F. PIEPER, both of Rochester, in the county of Monroe and State of New York, have invented certain new and useful Improvements in Fluid-Pumps; and we do hereby declare the following to be a full, clear, and exact description of the same, reference being had to the accompanying drawings, forming a part of this specification, and to the reference-numerals marked thereon.

Our invention relates to fluid pumps, with reference particularly to that class of devices designed for compressing air or other fluid, and it has for its object to improve the construction of such compressors, so as to afford an apparatus that can be economically manufactured, and will at the same time render the working parts readily accessible for adjustment and repairs.

A further purpose of the invention consists in providing a structure that is simple in its arrangement, and extremely efficient in operation, while reducing to a minimum the tendency of the parts to get out of order or operate in an imperfect manner.

To these and other ends the invention consists of certain improvements and combinations of parts all as will be hereinafter more fully described, the novel features being pointed out in the claim at the end of the specification.

In the drawings: Figure 1 is a side elevation of a pump, showing the application of the present improvements; Fig. 2 is a plan view of the same; Fig. 3 is a plan view, with the upper portions of the pump removed, and partly in section; Fig. 4 is a side view of the apparatus, showing the crank case and the valve chambers in section, and Fig. 5 is a transverse sectional view.

Similar reference characters throughout the several views indicate the same parts.

The invention is susceptible of various applications, and in the present embodiment, we have shown its use, for the purpose of illustration, in connection with a two cylinder air pump, A, A² designating the cylinders in which travel pistons such as indicated at B, while C are connecting rods pivoted to said pistons, and connecting them with the crank shaft C².

Attached to one side of the cylinders is a casing embodying a lower section D and an upper section D², the lower section being

held in place by means of the bolt D³. The lower section D of the casing embodies a pair of valve chambers D⁴ which are connected with the respective cylinders of the pump by means of ports D⁵, and passages D⁶ formed in the walls of the cylinders. In order to afford a tight joint between the casing D and the cylinder walls, the latter are provided with grooves surrounding the passages D⁶, and adapted to receive collars D⁷ formed on the casing around the ports D⁵, while D⁸ designate gaskets of rubber or other suitable material. The upper section D² of the casing rests directly upon the lower section D, an interlocking joint being afforded between them by means of the annular flanges such as D⁹ formed on the lower section of the casing and coöperating with corresponding grooves D¹⁰ on the upper section, suitable packing material being employed therein, and the sections are held together in a manner which will presently be more fully described. The lower valve chambers D⁴ are provided with valve seats E at their lower portions to receive valves E' which are preferably of disk formation, and adapted to close the openings E² leading to the bottom of the casing. The lower portions of the upper valve chambers are also provided with valve seats, which in the present instance are formed upon separate seat portions E³ having threaded engagement with the valve chambers and adapted to support the disk valves E⁴. The tops of the upper valve chambers are designated at E⁵, being separable from the upper section and connected thereto by a joint similar to that between the upper and lower sections of the casing, and they carry centrally depending portions E⁶ constituting stops to limit the upward movement of the valves E⁴. The valves E⁴ are held against their seats by means of springs E⁷ surrounding the stop portions E⁶ and abutting against lugs E⁸ formed upon the valves. The seat portions E³ carry depending stop portions E⁹ which extend downwardly into the lower valve chambers to limit the upward movement of the valves E', the latter being held in proper relation to their seats by means of springs E¹⁰ surrounding the stop portions E⁹ and engaging flanges E¹¹ upon the valves.

The seat portion E³ need not necessarily be formed separately from the upper section of the casing, and a construction in which the upper valve seats are formed integral with

the upper section of the casing is within the purpose of the present invention.

The upper valve chambers are connected with an air outlet F which may lead to a suitable air supply tank, while F² designates an air inlet supported at the bottom of a holder F³, which is attached to the lower section D of the casing and connects the air inlet thereto. The holder F³ is provided with suitable filtering means, consisting in the present instance of a mass of cotton F⁴ filling the interior thereof and surmounted by a cover F⁵ of wire gauze, or other suitable screening material. The air entering through the inlet F² passes upwardly through the filtering material, above the valves E and thence into the cylinders A² from which it is forced above the valves E⁸ and out through the passage F. The tops of the upper section are held in engagement with such section by suitable means which may operate at the same time to hold the upper section in engagement with the lower section of the casing, and this is preferably accomplished by a yoke member G arranged to engage the tops E⁵ of the upper section in the manner shown in Fig. 4, said yoke member being held in position by a bolt G² which engages the threaded opening in the lower section.

The crank case, designated at H, affords an oil reservoir at its base, which may be filled by removing the plug H², and H³ are dished portions or recesses in the base of the crank case adapted to receive the knobs or projections H⁴ carried by the crank connections, as the crank shaft is rotated, whereby the lubricating fluid is furnished to the upper parts of the case, and is thence fed to the crank shaft bearings through suitable passages H⁶, and openings H⁶ formed in the bushing H⁷. The bearings are provided with passages H⁸ arranged in spaced relation to the crank case and surrounding the crank shaft, the latter being provided with suitable projections, preferably in the form

of disks H⁹ fixed thereon, which rotate within said passages H⁸. Openings H¹⁰ afford communication between the passages H⁸ and the interior of the crank case, and by this construction, a continuous circulation of the lubricating fluid is maintained, around the crank shaft within the bearings until it reaches the projections H⁹, whence it is returned to the crank case through the passage H¹⁰. A removable plate H¹¹ is provided, to afford access to the interior of the crank case.

We claim as our invention:

In a pump, the combination with a cylinder and a piston therein, of a casing removably attached to said cylinder and embodying a lower section including a pair of valve chambers communicating with the cylinder, a second valve chamber separated from and mounted directly upon each of the first named chambers and each provided with an outlet passage, a seat portion removably carried by the lower portion of each of the upper chambers and having an integral valve seat, a disk valve engaging said seat, a removable top for each of the upper chambers having a downwardly projecting integral portion disposed centrally of the chamber and in the path of said valve to limit its upward movement, a valve seat formed integrally at the bottom of each of the lower chambers, a disk valve engaging each of the last mentioned seats, an integral valve stop portion formed upon the aforesaid seat portions and projecting centrally of the chambers into the path of the valves in the lower chambers, an air inlet connected with said lower section of the casing and an air filtering device attached directly at the bottom of said lower section and supported thereon.

OSCAR H. PIEPER,
ALPHONSE F. PIEPER.
